UNITED STATES PATENT OFFICE.

WALTER EVERETT MOLINS, OF DEPTFORD, LONDON, ENGLAND.

CIGARETTE-MAKING MACHINERY.

Application filed October 28, 1927, Serial No. 229,476, and in Great Britain December 8, 1926.

This invention is for improvements in or relating to cigarette making machinery, and more particularly to a heating device for use on a cigarette making machine of the continuous rod type, and has for its object the provision of means whereby the overlapping portions of the cigarette paper of the continuous rod may be sealed together in an extremely efficient manner.

10 The present invention consists of a heating device for use on a cigarette making machine of the continuous rod type, wherein a heating element comprises a series of projecting teeth or the like, arranged to extend into a series of corresponding transverse slots formed in the folder of the rod forming mechanism so as to bear upon the overlapping edges of the cigarette paper.

15 The invention is more particularly described with reference to the accompanying drawings, in which:

Fig. 1 illustrates in side elevation a heater constructed according to the present invention.

20 Fig. 2 is an end elevation of Fig. 1.

Fig. 3 is a section on the line A—A of a pin and slot connection mounted between the two heaters illustrated in Fig. 1.

25 Fig. 4 illustrates the heating element of one of the heating devices illustrated in Fig. 1.

Fig. 5 is an end view of Fig. 4.

Fig. 6 is a part plan of the folder illustrated in Fig. 1.

30 Figs. 7 and 8 are sections on the lines B—B and C—C of the folders illustrated in Fig. 6, and

35 Fig. 9 is an elevation of the folder illustrated in Fig. 6.

Referring to the drawings there is illustrated an electric heating element which 40 comprises a coil of resistance wire (not shown) and a bar 1 made from a good heat conducting material, such as copper. The heating element is mounted in a cylindrical casing 2 in such a manner that the bar 1 extends beyond the cylindrical surface thereof. The casing 2 is secured by a bolt 3 to an arm 4 which is mounted upon a spindle 5 carried upon a standard 6 supported upon 45 the frame of the cigarette making machine.

50 The position of the arm 4 may be adjusted by means of an adjusting screw 7 mounted on the arm 4 and adapted to engage with a projection 8 formed on the standard 6.

55 Secured to the arm 4 is a handle 9 by which

the heater may be moved about the axis of the spindle 5 so as either to rest, as illustrated in Fig. 2, upon the overlapping edges of the paper of a cigarette rod, or be raised 60 into a position out of engagement with the rod.

The bar 1 of the heating element is preferably provided with a series of projections 1^a which are adapted to extend into 65 a series of slots 1^b formed in the folder 11 of a cigarette making machine, so that when the heater is in engagement with the cigarette rod, the projections 1^a, together with the portions 1^c of the folder which lie between the projections 1^a, they maintain the 70 rod in the folded condition and simultaneously apply heat to the rod as the same is passing through the folder.

75 The heater which engages with the folder of the rod forming mechanism may be provided with a second heater, the heating rod 12 (Fig. 1) of which is in alignment with the rod 1 of the first heater, and the two heaters are arranged end to end so that the 80 cigarette rod is subjected to heat over substantially twice the distance of the normal cigarette rod heater, without increasing the length of the cigarette making machine.

85 The first heater is operatively connected to the second heater through the pin and slot mechanism illustrated in Figs. 1 and 3, whereby the first heater may be moved into and out of engagement with the cigarette rod without interfering with the second 90 heater, but it is arranged so that when the second heater is moved out of engagement with the rod, a projection 13 on the spindle 14 of the second heater engages with a pin 15 on the spindle 5 of the first heater and 95 automatically moves the first heater out of engagement with the cigarette rod.

If necessary, the heating element of the first heater may comprise a series of metallic discs spaced apart from one another 100 by heat insulating material and the discs may be arranged so as to extend into the transverse slots 1^b in the folder of the rod forming mechanism so that they bear upon the overlapping edges of the paper of the 105 cigarette rod. The discs may be heated in any desired manner, for example, by an electric heating element, and may, if necessary, be rotated so as to sweep over the overlapping edges of the paper of the cigarette rod 110 and act as a cleanser of the overlap as well as a heater.

Thus it will be seen that according to the present invention there is provided means whereby a heating element may be considerably increased in its length without increasing the ordinary dimensions of the cigarette making machine.

What I claim as my invention and desire to secure by Letters Patent is:—

1. In a heating device for use on a cigarette machine of the continuous rod type, the combination of a folder for forming the cigarette rod, said folder being provided with an aperture in the wall thereof, means for heating said rod, and a support for said means whereby the latter may be moved into and out of said aperture.
2. In a heating device for use on a cigarette machine of the continuous rod type, the combination of a folder for forming the cigarette rod, said folder being provided with an aperture in the wall thereof, means for heating said rod, a support for said means whereby the latter may be moved into and out of said aperture, and an adjustable member for limiting the movement of said means into said aperture.
3. A heating device for use on a cigarette making machine of the continuous rod type which comprises in combination a heating element having a series of projecting teeth formed on the heating surface thereof, and

a folder for forming the cigarette rod having a series of corresponding transverse slots arranged to receive the teeth of the heating element so that the same bear on the overlapping edges of the cigarette paper folded about the rod of tobacco.

4. A heating device for use on a cigarette making machine of the continuous rod type which comprises in combination a heating element having a series of projecting teeth formed on the heating surface thereof, a rod forming mechanism provided with a series of transverse slots arranged to receive the teeth of the heating element so that the same bear upon the overlapping edges of the cigarette paper folded about the rod of tobacco, a second heating element arranged to constitute a continuation of the heating surface of the first heating element and means operatively connecting said heating elements whereby the first heating element may be moved into and out of engagement with the cigarette rod without altering the position of the second heating element, whereas the first heating element is automatically moved out of engagement with the rod as the second heating element is moved into an operative position.

In testimony whereof I hereunto affix my signature.

WALTER EVERETT MOLINS.
